Introducing Russell Westbrook's Jordan Why Not ZERO.1 [online], [retrieved Jan. 24, 2018], Retrieved from Sneakernews.com [Internet] <URL: <https://sneakernews.com/2018/01/04/russell-westbrook-jordan-why-not-zero-1/>>; 20 color sheets, Dated Jan. 4, 2018.

Primary Examiner — T Chase Nelson(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design;

FIG. 2 is a bottom view thereof;

FIG. 3 is a rear perspective view thereof; and,

FIG. 4 is a rear view thereof.

The broken lines immediately adjacent to the shaded area define the bounds of the claimed design and form no part thereof. The broken lines showing the remainder of the shoe are for environmental purposes only and form no part of the claimed design.
